US0D1013028S

(12) **United States Design Patent** (10) Patent No.: **US D1,013,028 S**
(45) Date of Patent: ** Jan. 30, 2024

(54) **PAYMENT TERMINAL WITH OPTICAL CODE-READER**

(71) Applicant: **Panasonic Intellectual Property Management Co., Ltd.**, Osaka (JP)

(72) Inventors: **Yasuyuki Tanaka**, Kanagawa (JP); **Yasuji Wakiyama**, Kanagawa (JP); **Takeyuki Sasaki**, Kanagawa (JP); **Kohei Takada**, Kanagawa (JP); **Kyohei Kida**, Kanagawa (JP)

(73) Assignee: **PANASONIC INTELLECTUAL PROPERTY MANAGEMENT CO., LTD.**, Osaka (JP)

(**) Term: **15 Years**

(21) Appl. No.: **29/780,319**

(22) Filed: **Apr. 23, 2021**

(30) **Foreign Application Priority Data**

CLAIM

We claim the ornamental design for a payment terminal with optical code-reader, as shown and described.

DESCRIPTION

FIG. 1 is a front perspective view of a payment terminal with optical code-reader according to the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the drawings depict portions of the payment terminal that form no part of the claimed design.

1 Claim, 7 Drawing Sheets
